UNITED STATES PATENT OFFICE

GEORGES MEGROZ, OF BRONXVILLE, NEW YORK, ASSIGNOR TO THE UNITED PIECE DYE WORKS, OF LODI, NEW JERSEY, A CORPORATION OF NEW JERSEY

DESIGN FOR A TEXTILE FABRIC

Application filed October 12, 1932. Serial No. 45,324. Term of patent 3½ years.

To all whom it may concern:

Be it known that I, GEORGES MEGROZ, a citizen of the United States, residing at the city of Bronxville, in the county of Westchester and State of New York, have invented a new, original, and ornamental Design for Textile Fabrics, of which the following is a specification, reference being had to the accompanying drawing, forming part thereof.

The figure is a plan view of a textile fabric, showing my new design. The area within the dot and dash lines shows one com-

plete unit of the design. The repeats are arranged in vertical rows, and adjacent vertical rows are one half a complete unit offset so that the angle of the complete unit indicated by letter A corresponds with the angle B of one of the repeats in an adjacent vertical row.

I claim:

The ornamental design for a textile fabric, substantially as shown and described.

GEORGES MEGROZ.
